& Loane Atty's.

UNITED STATES PATENT OFFICE

GEORGE W. BARNES, OF KENOSHA, WISCONSIN, ASSIGNOR TO SIMMONS COMPANY, OF NEW YORK, N. Y., A CORPORATION OF DELAWARE

SAFETY LOCK FOR ROLLER BEDS

Application filed May 9, 1927. Serial No. 189,818.

This invention relates to safety locks for roller beds and deals with that class of bed in which the main bed frame is pivotally mounted on a portable wheeled carriage of relatively small base area, so that the entire bed structure may be wheeled into a closet, or other convenient place for storage, when the bedstead is not in use.

In such bedsteads, the main bed frame 10 which is not usually provided with anti-friction casters at the end, which engages the floor when the bedstead is extended, may or may not be provided with springs or other counter-weighting device to facilitate the 15 folding of the bedstead. In any case, after the bed has been unfolded it may be necessary or desirable to shift the position of the same in the room, and when doing so, horizontal force may be applied to the upstanding 20 portion of the carriage which forms the head frame of the bedstead. Such head frame may be a fixed part of the carriage. It will be obvious that because of the relatively short wheel base of the carriage from front to 25 rear, when such force is suddenly applied, and particularly when the bed frame is not provided with casters on its outer end, the resistance to the movement of the bedstead as a whole, over the surface of the floor of 30 the room will result in a tendency to overturn the carriage and cause the carriage to fall over onto the top of the extended bed frame.

This difficulty has to a certain extent, interfered with the sale of roller beds. It has been proposed to employ manually operated devices to lock the bed frame in extended position, but so far as I am aware, no-one has proposed or suggested a device in which 40 the bedstead is automatically made safe against such over-tipping or overturning of the carriage.

The principal object of the invention is to provide an arrangement by which improper 45 or accidental overturning of the carriage or improper folding of the carriage onto the bed frame is prevented; to provide an arrangement which shall be automatic in character and requires no additional movements or manipulation on the part of the operator;

to provide a construction which shall be simple, economical in design and manufacture, while being positive, fool-proof and efficient in operation, and in general, to provide an improved safety lock of the character referred to.

In the drawings which illustrate a specific application of my invention to a roller bed of the counterweighted type,

Fig. 1 is a fragmentary side elevation of 60 the carriage and associated parts.

Fig. 2 is a section taken on the line 2—2 of Fig. 1.

Fig. 3 is an enlarged view of certain portions of Fig. 1, showing the carriage in two 65 positions, and

Fig. 4 is a view of certain of the parts in Fig. 1, but showing the bed frame in vertical or folded position.

Referring now to the drawings, 10 represents a carriage, which is mounted upon four large diameter, smooth running caster wheels, the front wheels being designated 11 and the rear wheels being designated 12. The carriage is made with a rear frame member 13 which extends upwardly above the mattress of the bedstead when the latter is extended, and constitutes the head frame of the bedstead. The bed frame 14 of the usual type, and of the customary length, includes 70 a pair of side rails from which depend a pair of small brackets 15. These small brackets 15 are fitted with bearings 16, which pivot on pins 17 secured in the side members 18 of the carriage 10.

In the present instance, the bed frame 14, which is of the coil spring type, is fitted with the usual cross slats 19 and coil springs 20, on which the mattress is supported. A counter-weight 21 is provided at the inner end of the bed frame so as to assist the operator during the folding movement of the bed frame about the pivots 17. Suitable cross members as at 22 may be furnished to maintain the side members at the proper spacing.

Describing now the improved safety device, it will be seen that on one of the side members of the folding bed frame, there is mounted a headed pin or rivet 23 from which pin 23, there is pivotally hung or supported 100

a latch or link 24. Said latch 24 is made with a slot 25 which accommodates the shank of a headed pin 26 rigidly secured in the side frame 18 of the carriage at a point considerably lower than the main bed frame pivot 17. The link pivot 24 is positioned in the bed frame 14 adjacent the pivot 17 and is located above the pin 26 so that when the parts are in the position shown in Fig. 1, the stop or pin 26 on the carriage is located in the lower end of an oblique portion 27 at the lower end of the vertical portion of the slot 25. It will be observed that the upper end of the oblique slot 27 extends upwardly and laterally past the lower end of the vertical portion of the slot 25 so as to provide a notch 28.

Ordinarily, as long as the carriage is resting upon all fours, i. e., while it maintains its normal vertical position, there will be no tendency for the pin 26 to enter the notch 28, as when the bed frame is folded on pivots 17, the position of the upper pin 23 with reference to a vertical line passing through the headed pin 26, will not change materially, and the pin 26 will therefore follow around the corner 29 and into the vertical portion 30 of the slot 25 without entering the notch 28. It is understood that the link 24 hangs freely by gravity from the pin 23, and normally tends to hang in the position shown in Fig. 1. After the link pivot 23 commences to move down into the position shown in Fig. 4 of the drawings, the stop pin 26 will cause the link 24 to assume an off-vertical position, but since, by that time the pin 26 has moved above the notch 28, said pin 26 will thereafter slide up into the upper end of the slot, as indicated in Fig. 4, and the folding movement of the bed frame on the carriage will not be interfered with.

Assuming however, that, with the bed frame in extended or unfolded position, it is desired to move the bedstead to another part of the room, or if for any other reason force be applied to the upper part of the head frame 13 in such direction as to push said upper part towards the foot end of the bed frame, because of the free running character of the casters 11 and 12, the relatively narrow or short wheel base between the centers of the casters 11 and 12, and because the center of gravity of the structure is relatively close to the front casters 11, there may be a tendency for the carriage to tip over toward the bed frame into the position shown in full lines in Fig. 3. When this occurs, although the relative positions of the pivots 17 and 23 will not change materially, there will be on the other hand, a very material shift of the pin 26 rearwardly from the vertical line passing through pivot 23 and this will cause the said pin 26 to move over into the rear notch at the upper end of the oblique portion 27 of the slot 25. When this occurs, and when the

stop pin 26 engages in the notch 28, further relative pivotal movement of the bed frame and carriage 10 is arrested. Hence, the carriage is automatically prevented from overturning or folding up over the bed frame.

It will be observed that with this arrangement it is not necessary to lock the bed frame to the carriage against relative pivotal movement thereon, after unfolding the bedstead, since the preventing of the overturning or improper folding of the carriage on the bed frame is entirely automatic. Furthermore, there is no interference with the normal folding or unfolding movement of the bed frame on the carriage, and no extra manipulations on the part of the operator are demanded.

The described details of construction being illustrative of only a single application of my invention, it will be understood that the scope of the same should be determined by reference to the appended claims, said claims being construed as broadly as possible, consistent with the state of the art.

I claim as my invention:

1. In a roller bed, the combination of a movable wheeled carriage having a relatively short wheel base, a relatively long bed frame pivoted on the carriage and adapted to swing thereon from vertical folded position to extended horizontal or unfolded position, a link pivotally connected to said frame and freely suspended from its pivot, and a stop on said carriage, said link and stop being normally out of operative engagement so as not to interfere with normal folding or unfolding of said bed frame, but adapted to automatically cooperate to limit accidental tipping of the upper part of said carriage inwardly over the bed frame when the latter is in unfolded position.

2. In a roller bed, the combination of a movable wheeled carriage having a relatively short base, a relatively long bed frame pivoted on the carriage and adapted to swing thereon from vertical normal folded position to extended horizontal or unfolded position, a link pivotally suspended from said frame and a stop on the carriage, adapted, when the bed is in unfolded position, upon tipping of the upper part of the carriage towards the bed frame to effectively engage said link and thereby prevent further tipping of the carriage, the force of gravity tending to prevent operative engagement of the latch and the stop during pivotal movement of the bed frame on the carriage so long as the carriage is maintained in its normal vertical position.

3. In a roller bed, the combination of a movable wheeled carriage having a relatively short base, a relatively long bed frame pivoted on the carriage and adapted to swing thereon from vertical normal folded position to extended horizontal or unfolded position, a link pivotally suspended from a point on that frame adjacent the frame pivot, and a

stop on the carriage below the frame pivot, adapted, when the bed is in unfolded position, upon tipping of the upper part of the carriage towards the bed frame to effectively engage said link and thereby prevent further tipping of the carriage, the force of gravity tending to prevent operative engagement of the latch and the stop during pivotal movement of the bed frame on the carriage so long as the carriage is maintained in its normal vertical position.

4. In a roller bed, the combination of a bed frame and a portable carriage on which said bed frame is pivotally mounted so as to be adjustable from vertical folded position to horizontal extended position, and a safety device operative when the bed is in extended position to limit tipping of the carriage inwardly over the adjacent end of the bed frame, said device comprising a pair of normally slidably interengaging members mounted respectively on said bed frame and on said carriage, one of said members being movably mounted and the other being fixedly mounted on the respective part carrying the same, said movable member having a portion engaging said fixed member and provided with a portion for restricting rotation between said bed frame and said carriage from extended to folded position, said restricting portion of said movable member being brought into operative engagement with said fixed member as an incident to the tipping of said carriage toward the bed frame, and said restricting portion being ineffective upon the normal folding of said bed frame.

5. In a roller bed, the combination of a bed frame and a portable carriage on which said bed frame is pivotally mounted so as to be adjustable from vertical folded position to horizontal extended position, a safety device for limiting tipping of the carriage inwardly over the adjacent end of the bed frame when the latter is in extended position, said safety device comprising a stop member carried by one of said parts, and a link pivoted to the other part and having a slot for receiving said stop member and in which slot said stop member is free to move relative to the link during normal folding or unfolding movement of the bed frame relative to the carriage, said slot being formed with an offset part adapted to receive said stop to limit relative movement of the stop and link when the carriage tips inwardly over the bed frame, thereby to limit such tipping of the carriage.

6. In a roller bed, the combination of a bed frame and a portable carriage on which said bed frame is pivotally mounted so as to be adjustable from vertical folded position to horizontal extended position, and a safety device operative when the bed is in extended position to limit tipping of the carriage inwardly over the adjacent end of the bed frame, said device comprising a pair of

normally slidably interengaging members mounted respectively on said bed frame and on said carriage, one of said members being pivotally mounted and the other being fixedly mounted on the respective part carrying the same, said pivoted member having a portion engaging said fixed member and provided with a portion for restricting rotation between said bed frame and said carriage from extended to folded position, said restricting portion of said pivoted member being brought by gravity into operative engagement with said fixed member as an incident to the tipping of said carriage toward the bed frame, and said restricting portion being retained by gravity out of operative engagement with said fixed member upon the normal folding of said bed frame.
